UNITED STATES PATENT OFFICE.

WILLIAM J. BODA, OF DAYTON, OHIO, ASSIGNOR OF ONE-HALF TO LEE M BODA, OF COLUMBUS, OHIO.

METHOD OF UNITING WOODWORK.

SPECIFICATION forming part of Letters Patent No. 787,429, dated April 18, 1905.
Application filed December 9, 1904. Serial No. 236,114.

To all whom it may concern:

Be it known that I, WILLIAM J. BODA, a citizen of the United States, residing at Dayton, in the county of Montgomery and State of Ohio, have invented certain new and useful Improvements in Nails and Methods of Concealing Same in Interior Finish and Fancy Woodwork; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a new and useful method for uniting interior finish in buildings and other fine woodwork—such, for example, as buggy-work, cabinet-work, mantels, &c., and all kinds of woodwork where the surface is finished either in oil, varnish, or paint.

The object of the invention is to provide means for uniting said parts and whereby the nails driven through the woodwork from the exposed surface will not leave any indication or sign in the surface of the wood of their entrance. In other words, the fibers or grain of the wood is enabled to close the wound or incision in the wood, so that the head of the nail after the latter has been countersunk in the wood is invisible, and the use of putty in closing the wound or incision is avoided.

The nail is preferably oval or oblong in cross-section, so that it acts as a wedge, and is driven into the wood with its greatest cross-sectional width lying parallel with the fibers or grain of the wood. The fibers or grain of the wood are thus separated at the point where the nail enters.

Preceding a detail description of the invention reference is made to the accompanying drawings, of which—

Figure 1 is a perspective view of a block of wood, showing an incision being made therein for the initial entrance of the nail by means of a chisel. Fig. 2 is a sectional view showing the edge of the chisel and the extent or depth of the incision. Fig. 3 is a perspective

view showing the nail being driven through the incision. Fig. 4 is a similar view showing the completion of the driving of the nail and the same countersunk, leaving the wound or incision in the exposed surface of the wood. Fig. 5 is a similar view showing the nail wound or incision as nearly closed by two side incisions upon which moisture or liquid compound is placed. Figs. 6 and 7 are details of the forms of chisel for making the nail incision and the side incisions in the wood. Fig. 8 is a perspective view of the block as it appears after the nail has been driven and the incision closed by means of the side incisions shown in Fig. 5 and the application of moisture or liquid compound.

In a detail description of the invention similar reference characters indicate corresponding parts.

In carrying out the method a chisel 1, having a cross-sectional shape similar to the nail, is employed to make the initial incision 2, which is preferably about one-eighth of an inch deep and about the depth of the nail-head. This incision in the surface of the wood is essentially parallel with the grain thereof. The nail 5 is then driven and countersunk by means of a nail set or punch of the shape of the nail-head. After the nail is countersunk a chisel 3 is employed to make parallel incisions 4 on each side of the nail incision. The point of this chisel tapers on one side in order that the outer side of the incisions 4 will be straight, while the inner side of said incisions will slant in the direction of the nail incision 2. These incisions 4 need be only of a depth sufficient to enable the fibers or grain of the wood to contract or come together over the head of the nail—that is to say, the side incisions 4 need not extend down to a point on a level with the head of the nail; but they should be of sufficient depth to enable the fibers to contract above the head of the nail to completely close the nail incision. In the use of the smaller sizes of nails the side incisions 4 may be dispensed with. The natural tendency of the fibers or grain of the wood is to contract or come together, and this natural tendency is aided by applying to

the incisions moisture in the form of water or in the case of oak or cherry a liquid compound composed of water, whiting, and pigments of colors suitable to the wood. The chief requisite of this compound is its moisture, and the same is applied to the incisions by means of a small sponge holding but a few drops, which when entering the incisions has the effect of accelerating the tendency of the fibers or grain of the wood to come together, and thus close the incisions, thereby leaving the surface of the wood as if no nail had been driven therein. It may be further stated that the liquid compound in addition to its action as above indicated neutralizes the effect of the acid in the wood when the liquid or moisture comes in contact with the nail, thus leaving a nice, clean, and bright joint where the incision has been made and the nail passed through; otherwise the action of the acid which is inherent in the wood coming in contact with the metallic nail would leave a black streak in the wood at the point of incision. The chisel incisions 4 4 on either side of the nail incision being small and also running parallel with the grain of the wood assists the grain inclosing the greater incision—to wit, the nail incision—so that in a short period the grain of the wood unites and closes said nail incisions so completely that it is impossible to tell where the nail has been driven after sandpapering and varnishing the surface of the wood.

Having described my invention, I claim—

1. The herein-described method of uniting 35 interior finish and other fine woodwork, so that the nail incisions are closed without the use of putty, said method consisting in separating the grain or fibers of the wood in the surface thereof by making an incision parallel 40 with the grain, in driving a nail oblong in cross-section through said incision and countersinking the head thereof, and in applying

moisture to the wound or incision after the nail has been countersunk.

2. A method of uniting parts of interior 45 finish and other fine woodwork so that the initial incisions for the nails will not be visible, and the use of putty in filling such incisions is obviated, said method consisting in making an incision in the surface of the wood parallel 50 with the grain thereof, in driving a nail which is oblong in cross-section, through said incision and countersinking the head of said nail beyond the exposed surface of the wood, and in further making parallel incisions 55 adjacent to the incision of the nail, and in subsequently applying to said incisions, moisture whereby the fiber or grain of the wood is caused to close said incisions, substantially as set forth.

3. A method of uniting parts of interior 60 finish and other fine woodwork so that the incisions will become invisible without the use of putty, said method consisting in making an oblong incision in the surface of the wood 65 parallel with the grain thereof, in driving a nail oblong in cross-section through said incision with the greatest cross-sectional width of said nail parallel with the grain of the wood, and in countersinking the head of said 70 nail below the surface of the wood, in making an oblong incision on either side of the nail-incision and parallel therewith, and in applying to said incisions a liquid compound consisting of water, whiting and a pigment whereby the said incisions are caused to close and the effect of the acid in the wood coming in contact with the metallic nail is neutralized.

In testimony whereof I affix my signature in presence of two witnesses.

WILLIAM J. BODA.
